[57] CLAIM

The ornamental design for a multi-outlet center, as shown and described.

DESCRIPTION

FIG. 1 is a perspective view of a multi-outlet center showing our new design;

FIG. 2 is an elevational view of a first side thereof;

FIG. 3 is a top plan view thereof;

FIG. 4 is a rear elevational view thereof;

FIG. 5 is a front elevational view thereof; and

FIG. 6 is an elevational view of a second side thereof. The portion of the power cord is shown in broken lines for illustrative purposes only.

FIG. 1

FIG. 2

FIG. 3

FIG. 4

FIG. 5

FIG. 6
